UNITED STATES PATENT OFFICE.

GEORGE GEGENHEIMER, OF BROOKLYN, NEW YORK, ASSIGNOR TO JAMES C. ELMS,
CHARLES H. SELLON, AND FRANKLIN M. ELMS, OF NEW YORK, N. Y., COPARTNERS.

DESIGN FOR TEXTILE FABRIC.

41,311.

Specification for Design.

Patented Apr. 11, 1911.

Application filed February 1, 1911. Serial No. 606,055. Term of patent 3½ years.

To all whom it may concern:

Be it known that I, GEORGE GEGENHEIMER, a citizen of the United States, residing at 1466 East Fourth street, Brooklyn, in the county of Kings and State of New York, have invented a new, original, and ornamental Design for Textile Fabrics, of which the following is a specification, reference being had to the accompanying drawing, forming a part hereof.

The figure is a plan view of a portion of a textile fabric showing my new design.

I claim:

The ornamental design for a textile fabric, as shown.

GEORGE GEGENHEIMER.

Witnesses:

JAS. M. DOREMUS,
MRS. G. GEGENHEIMER.

Copies of this design may be obtained for five cents each, by addressing the "Commissioner of Patents, Washington, D. C."
